Inventor
 Frank Allen

United States Patent Office.

FRANK FULLER, OF NEW YORK, N. Y.

Letters Patent No. 71,782, dated December 3, 1867.

TOY GUN OR PISTOL.

The Schedule referred to in these Letters Patent and making part of the same.

TO ALL WHOM IT MAY CONCERN:

Be it known that I, FRANK FULLER, of the city, county, and State of New York, have invented certain new and useful Improvements in the Mode of Constructing Toy Guns or Pistols; and I hereby declare that the following is a full and exact description thereof, reference being had to the accompanying drawings, and to the letters of reference marked thereon.

The nature of my invention consists in the construction of a toy gun or pistol with a barrel and a diagonal spring-chamber, the barrel being used for the projectile and for the hammer or rod which discharges it, the diagonal spring-chamber being employed to receive and conceal the India-rubber strip or band, which, being attached to and concealed within the head or back end of the hammer or discharging-rod, actuates it, and produces the discharge of the projectile.

It consists, further, in the means of cocking the piece and detaining it ready for discharge, and also of the means of discharging it; the object of the invention being the production of a toy gun or pistol which shall be efficient in its action, durable in its qualities, symmetrical and attractive in appearance, simple and inexpensive in construction, while at the same time involving the operations of cocking and discharging common to most varieties of fire-arms in use by "children of a larger growth."

To enable others skilled in the art to make and use my invention, I will proceed to describe its construction and operation.

Figures 1 and 2 represent vertical sections of the weapon.

Figures 3, 4, 5, 9, and 10, represent side views.

Figure 6 represents a top view of the projecting plate.

Figures 7 and 8 are end or muzzle views.

A is the stock of a pistol or gun. B is the barrel, which may be simply a continuation of the stock, or may be formed of a separate piece. a' is a diagonal spring-chamber, which is a groove formed in the stock. D is an India-rubber strip or band, concealed in the diagonal spring-chamber, and attached to the stock A or barrel B by means of a pin or other suitable device, as shown at a" in figs. 1, 5, and 9, and also to the hammer or discharging-rod C within the head or back end of the hammer b. s, figs. 1 and 2, is a groove on the under side of the head b of the hammer or discharging-rod C, in which groove is placed a pin or upright, to which the elastic strip or band D is attached, thereby furthering the object of concealing and protecting said strip or band. F, fig. 9, is a discharging-lever, which may be attached to the outside of the stock A, or be so let in below the surface as to protrude slightly at the portion to be grasped by the hand, only when the weapon is cocked, and is designed to act in lieu of the trigger—which, when this method is employed, may be a mere pin or imitation trigger only—by acting as a lever when grasped to elevate the back end b of the discharging-rod C over the detaining-notch c', and thereby releasing it. G, figs. 5 and 6, is a covering or encasement for the back end b of the discharging-rod C, and the portion of the stock traversed by it. d, fig. 5, is a slot in the sides of the encasement G, through which appears the head of pin v, which pin passes through or connects with the back end of the discharging-rod C, and may be used in the act of cocking the weapon. Fig. 6 is a top view of the encasement G, with a slot, f, through which may pass the cock or top of the back end b of the discharging-rod C, (see fig. 5,) should this method of cocking the weapon be found preferable. h, figs. 2 and 4, is a spring, attached to the barrel B, or to the stock A, or to the encasement G, and is intended to depress the head or back end b of the discharging-rod C into the detaining-notch c' as the rod is drawn back. It may be slotted to correspond with the slot f in the top of encasement G, to admit the passage of the top b of the back end of the discharging-rod C, which forms a cock. g, figs. 3 and 4, is a stop to prevent the discharging-rod C from being drawn so far back as to injure the elastic strip or band D. This stop may be formed by a simple elevation in the stock A, or may be a part of the discharging-lever F, when the method of discharging the piece shown in fig. 9 is adopted.

Fig. 1 shows the weapon discharged. Fig. 2 shows the position of the parts prior to the discharge. It will be seen that the discharging-rod is drawn back, and is detained in its position by being depressed into the detaining-notch c', which notch is more clearly shown in figs. 3, 4, and 9. The upper portion of the trigger E is wedge-shaped, and when the trigger is pressed by the finger, the upper part, acting as a cam, elevates and

releases the discharging-rod C, which is drawn suddenly and forcibly forward to the barrel B by the contractile power of the India rubber, D, and by this means the projectile is discharged.

In fig. 10 another means of cocking, as well as of discharging the piece, is shown. The loop J is made to form a substitute for a trigger and cock, and is connected with the head b of the discharging-rod C, (around which, together with the stock A, it is made to pass,) by the pin n. Backward pressure by the application of the finger upon the upper part of this loop or encircling-plate J, withdraws the discharging-rod until its head falls into the detaining-notch c', and backward pressure upon the lower part of said loop elevates and releases the discharging-rod, and discharges the weapon.

In fig. 9 the dotted lines i are intended to represent external India-rubber bands, which may be applied over the hammer-head or back end of the discharging-rod b, and extended to some point of attachment upon the stock or barrel, as shown at a'', thereby affording a ready means of increasing the efficiency of the weapon, as well as of instantly repairing it in case the concealed elastic strip or band should become injured.

I do not claim the use of an elastic India-rubber spring as a means of actuating the discharging-rod of a toy gun or pistol, as this is in common use; neither do I claim the employment of a discharging-rod working in the barrel of such a toy for the purpose of discharging the projectiles; nor do I claim a spring-chamber opening into or communicating with the interior of the barrel of the weapon.

But what I claim as new, and desire to secure by Letters Patent of the United States, is—

The combination of the discharging-rod C, constructed with a grooved head, b, the spring D operating in the spring-chamber a', substantially as set forth. The wedge-shaped trigger E, arranged to elevate and release the discharging-rod C and the shoulder c', with the stop g and depressing-spring h, all constructed substantially as set forth and described.

In testimony whereof, I hereunto subscribe my name in the presence of two witnesses.

FRANK FULLER.
